VENETIAN BLIND

Richard Laborda, Brooklyn, N. Y., assignor to
 Lowe Paper Company, Ridgefield, N. J., a corporation of New Jersey

Application March 19, 1940, Serial No. 324,757

5 Claims. (Cl. 156—17)

This invention relates to Venetian blinds and more particularly to a novel form of construction for controlling the raising and lowering of the louvers thereof, for tilting the louvers and for retaining them in any desired position of adjustment.

It has been the practice to mount Venetian blinds on specially constructed brackets which are usually provided with locking devices which cooperate with the blind to retain its louvers in a desired position of adjustment. In other constructions the supporting brackets have been connected with a supporting member for eyes which guide the lift cords which serve to raise and lower the blind. In all such constructions the blind is more or less permanently associated with its supporting brackets, and it is usually not possible to readily remove the entire blind, including the louver control cords, from its supporting brackets.

It is a purpose of the present invention to provide a Venetian blind structure in which the above noted disadvantages are overcome and in which the control features of the blind are so arranged that the blind may be supported on a pair of brackets of the type usually employed for supporting window shades, so that the installation or removal of a blind may be easily and quickly effected.

The lift cords, which serve to raise and lower the louvers of Venetian blinds, usually pass through a guide secured to one end of the top-most member of the blind and within which they often become twisted together and jammed with the result that it is not possible to raise or lower the blind until the cords have been straightened out. It is an object of this invention to provide a guide means for the lift cords which prevents them from twisting and becoming jammed, but retains them in proper parallel relation as they pass therethrough.

It is a further object of the invention to provide, in association with such a guide means for the lift cords, a holding pawl which serves to clamp them and thereby retain the louvers of the blind at any desired height.

Another object of the invention is to provide in association with the guide means for the lift cords a simple form of tilting device for tilting the blind louvers over their full range from a position in which they overlap each other to a position in which they are parallel and permit the maximum passage of light and air through the blind.

In pursuance of the last-named object, it is a

cognate object of the invention to control the tilting device by means of a single pull cord and to provide a novel form of combined guide and latching device for guiding the pull cord during its adjustment and for easily and quickly securing it in adjusted position.

Other and further objects of the invention will become apparent to those skilled in the art as the description thereof proceeds. For a better understanding of the invention, reference is made to the following description taken in connection with the accompanying drawings in which:

Fig. 1 is a front view, broken vertically and laterally, taken from the room side of a window, of a blind embodying the invention;

Fig. 2 is a side view of the blind shown in Fig. 1, a portion of the window casing also being shown in section;

Fig. 3 is a view of the top portion of the blind of Fig. 2 with the blind adjusted into open position;

Fig. 4 is a front sectional view of a portion of the blind of Fig. 6, taken on the line 4—4 thereof, showing the guide and latching means for the pull cords;

Fig. 5 is a view similar to Fig. 4 showing the latching means in locking position;

Fig. 6 is a top view of the blind of Fig. 4 but with the pull cords omitted;

Fig. 7 is a front view of a latch and guide for the pull cord of a blind embodying the invention, showing also a short section of the pull cord; and

Fig. 8 is a side view of the latch and section of pull cord shown in Fig. 7.

Referring to Figs. 1 and 2, the invention is shown as applied to a Venetian blind comprising a main revoluble supporting member or strip 1 carrying at its opposite ends the pivotal support pins 2 and 3 which are preferably positioned above and somewhat to the right of the center of the strip 1, as shown in Fig. 1. The strip 1 is preferably made of a light material such as wood and the pivotal support pins 2 and 3 may be secured therein in any preferred manner. The pin 2 is shown as entering a circular aperture in the end of a bracket 4 while the pin 3 is supported in a bracket 5 provided with an open slot 6 for ready entrance of the pin therein, the brackets 4 and 5 being of the type commonly employed for the mounting of window shades and being shown secured to the vertical sides of a window frame W.

Pendent from the supporting strip 1 and secured thereto, as by the nails 7, are a pair of ladder tapes 8, 9 each having a forward reach

10 and a rearward reach 11 (Figs. 2 and 3). The tapes 8, 9 are composed of woven textile material and disposed between their reaches 10, 11 are the louvers 12, whose opposite edges are secured to the tapes by any suitable means, not shown. The louvers 12 may be formed of any suitable light material, such as wood, or a light interior core covered with suitably colored paper.

For the purpose of raising and lowering the blind, a pair of pull cords 13, 14 (Fig. 1) are provided, the cords having portions passing upwards through guide eyes 15, 15' and 16, 16' secured to the front reaches 10 of the tapes. Just below the eyes 15, 16 the ends of the lift cords are enlarged, as indicated at 17, to engage the eyes 15, 16 and thereby lift the blind. Above the guides 15, 15' the lift cords pass through another pair of guide members 18, 18' which may be secured to the supporting strip 1 by the nails 1, the guides 18, 18' being curved so as to direct the cords 13, 14 toward the guiding and clamping device C, as shown in Fig. 1.

The device C comprises a bracket B, preferably made of thin sheet metal and having the spaced apart front and rear parallel plates 19, 20 connected together at one end by a curved end portion 21, as shown in Fig. 6. The plates 19, 20 are spaced apart a distance slightly greater than the diameter of the lift cords 13, 14 which pass between them freely, as shown in Figs. 4 and 5. To secure the bracket B in position with the rear plate 20 in contact with the front face of supporting strip 1, as shown in Fig. 6, a pair of wood screws 22, 23 pass through openings provided in the plate 19 and into the strip 1. The screw 23 is provided with a cylindrical portion 24 which is reduced to provide a shoulder 25 for engagement with the rear plate 20 (Fig. 6), whereby the portion 24 serves as a pivotal support for a holding or clamping pawl 26, which is adapted to move freely between the plates 19 and 20. The lower end of the pawl 26 is formed to provide a plurality of teeth 27 adapted for firm gripping engagement with the cord 14, as shown in Fig. 5. A guide pin 28 (Fig. 6) is driven into the supporting strip 1 and is provided with a projecting flange 29 adapted to engage the front face of the strip 1, and a cylindrical end portion 30 over which the cord 14 passes and which serves to support the vertically depending portion of the cord in proper position with reference to the end of the pawl 26. The pull cord 13 passes over the screw 22 which is arranged to keep its vertically depending portion close to the curved end wall 21 of the bracket, as shown in Figs. 4 and 5. The lower end of plate 20 is upset to form an outwardly projecting tooth 31, as shown in Figs. 4 to 6, and which serves as a backstop to limit the movement of pawl 26 toward the left and to retain its end in proper position for engagement with lift cord 14. As shown in Figs. 1 and 4, the front plate 19 extends substantially higher than the rear plate 20 and thereby serves to conceal the plate 20 and also the pawl 26 and guide pin 28.

The bracket B is also provided with a rearwardly extending flange 32 which engages the right end of the strip 1, the upper end of flange 32 being bent at right-angles, as shown in Figs. 2 and 4, to provide an overhanging flange 33 provided near its forward end with a circular aperture 34 and at its rear edge with a semi-circular notch 35, see Fig. 6. A substantially vertically depending tilting cord 36 passes through aperture 34 and has a knotted end 37 adapted to engage the flange 33, the cord passing rearwardly and

being seated in the notch 35 when the blind is closed, as shown in Fig. 2.

As a feature of the invention, a suitable form of latching device D is provided which serves both as a means for guiding the tilting cord 36 during the adjustment of the blind and also for securing it in a desired position of adjustment. The latch D comprises (see Figs. 7 and 8) a main body portion preferably formed of sheet metal and which includes the front wall 38, spaced side walls 39 and 40 which are bent outwardly to provide the spaced flanges 41, 42 adapted to be clamped in position against the front face of the window frame W. The latch is adapted to be secured in position by a pair of wood screws 43, 44 passing through the front wall 38 and disposed a suitable distance apart, as shown in Fig. 7, so that the cord 36 depends vertically between them. The side wall 39 is cut away at its lower edge to provide a tapered notch 45 into which the cord 36 becomes seated when it is looped about the latch, as shown in Fig. 1, to retain the supporting strip 1 and the blind louvers 12 in a desired position of adjustment. The front wall 38 is extended upwardly to provide a guide finger 46 whose upper portion is rearwardly depressed to form a conical tip 47 which serves to direct the looped end of the cord 36 rearwardly against the vertical portion of the cord, while the cord is being looped about the latch. The lower end of cord 36 is provided with a pull handle of suitable shape, as indicated at 48 in Fig. 1.

The blind will ordinarily assume the closed position shown in Figs. 1 and 2, with the louvers 12 overlapping each other, since the pivots 2 and 3 are not disposed in the axis of supporting member 1 but above such axis. To open the blind, the handle 48 is pulled vertically downwards, the screws 43 and 44 serving to properly guide the tilt cord 36 through the latch D. This action causes the supporting strip 1 to rotate in a clockwise direction about the pivotal supports 2 and 3, thereby raising the front reaches 10 of the ladder tapes 8, 9 and lowering their rear reaches 11, thus increasing the opening between successive louvers. This action may be continued until the louvers 12 are horizontal, as indicated in Fig. 3, at which position the maximum passage of light and air between them is realized. When in the desired position of adjustment, the lower end of tilt cord 36 is looped about the latch D in the manner above described into the position shown in Fig. 1. The cord 36 in cooperation with the latch D will now hold the blind in the adjusted position, as desired.

To raise the blind from its fully lowered position, as shown in Fig. 1, the lower end 49 of the lift cords 13, 14 is pulled vertically downwards, thus raising the eyes 15, 16 and the lowermost group of louvers 12. Continuance of this action causes the raising of successively higher portions of the tapes 8, 9 and their attached louvers. To retain the blind at a desired height, the end 49 of the lift cords is moved to the left until the cords 13, 14 assume the position indicated in dot and dash lines in Fig. 4 when the cord 14 is in biting engagement with the end of pawl 26. Upon now allowing the end 49 of the cords to raise slightly, the weight of the raised portion of the blind causes the portions of the cords 13, 14 opposite the pawl 26 to move upwardly and the pawl 26 to raise into its locking position, as shown in Fig. 5, with the pawl teeth 27 in firm engagement with cord 14 and with cord 13 pressed into firm frictional engagement with the curved end wall

21 of bracket B. The end 49 of the lift cords may now be released and the cords 13, 14 will depend vertically with the blind locked in its elevated position.

To lower the blind, the end 49 of the lift cords 13, 14 is pulled downwards a small amount to release the teeth 27 of pawl 26 from the cord 14, the pawl dropping into its lowered position in contact with the backstop 31, as shown in Fig. 4. The end 49 of the cords is now permitted to rise vertically until the blind is fully lowered or until it is partially lowered, in which case it is locked in the partially lowered position in the manner above described.

I have described what I believe to be the best embodiments of my invention. I do not wish, however, to be confined to the embodiments shown, but what I desire to cover by Letters Patent is set forth in the appended claims.

I claim:

1. In a Venetian blind including a tilttable top rail and a plurality of lift cords adapted to raise the louvers of the blind, a device for tilting and locking the louvers in an adjusted position, said device comprising a bracket having front and rear parallel plates spaced apart a distance only slightly greater than the diameter of the lift cords and an end wall connecting said front and rear plates, the lift cords passing through said bracket and having depending portions extending in parallel relation alongside said end wall, a locking pawl mounted between said front and

5 rear plates and arranged to urge only one of the lift cords into frictional engagement with said end wall and means for attaching the rear plate of said bracket to the front face of the tilttable top rail of the blind.

2. A locking device as set forth in claim 1 in which said bracket attaching means comprises a screw which also serves to pivotally support the locking pawl.

10 3. A locking device as set forth in claim 1 in which said bracket attaching means comprises a screw over which one of the lift cords passes and which serves to guide a depending portion thereof alongside the end wall of the bracket.

4. A locking device as set forth in claim 1 in which the front plate of said bracket extends to a level substantially above the top of the rear plate thereof and a member is secured in the top rail of the blind and has a portion projecting from the front surface thereof at a level above the rear plate, said projecting portion being arranged to guide a depending portion of one of the lift cords alongside the locking pawl.

20 25 5. A locking device as set forth in claim 1 in which the bracket is provided with an integrally formed, rearwardly extending plate adapted to engage the end of the top rail, said extending plate at its upper end being bent over to provide a projecting flange adapted to support a depending cord for tilting the blind.

RICHARD LABORDA.
